THERMOSTATIC SWITCHING DEVICE

Robert A. Watson, St. Louis, Mo., assignor to
Missouri Automatic Control Corporation, St.
Louis, Mo., a corporation of Missouri

Application March 2, 1951, Serial No. 213,507

8 Claims. (Cl. 200—140)

1

This invention relates to snap-action thermostatically actuated switches, particularly to those employing thermostatic actuators of the type having relatively small, though relatively positive movement in response to temperature change, and to motion transmission means for suitably multiplying these movements for operation of the switch.

Although this type of temperature responsive actuator provides a more positive and therefore more reliable primary movement, this movement is relatively small and must be greatly multiplied for snap-action operation of the switch contacts. It is also necessary to adequately multiply and transmit these small movements without loss or variation due to reversal of stresses as the actuator reverses its action, due to directional temperature change, while movement is resisted by the snap-action means. While it is, of course, necessary to provide a predetermined degree of flexing at some point in a transmission mechanism between the actuator and the switch contacts in order to achieve the desired snap action, any other motion losses, however, which may be due to uncontrolled flexing or looseness in the mechanism, would result in an unduly wide and unpredictable switch operating differential and are, therefore, to be avoided. It is further desirable that the means for multiplying and transmitting the movements of the actuator be of simple construction with a minimum number of members and of compact design.

It is, therefore, an object of this invention to provide a generally new and improved switching device of the above character, having a motion transmission mechanism which is simple and dependable in operation, and in which the required relatively great multiplication of the movements of the temperature actuator is achieved in a compact arrangement.

A further object is to provide in a switch as above, a motion transmission mechanism comprising a simple lever multiplication system in which the great multiplying effect of a collapsing toggle joint is employed to achieve, in a compact design, the required multiplication of the movements of the temperature responsive actuator.

A further object is to provide in a switch as above, a motion transmission system comprising a simple lever multiplication system of rugged and dependable construction in which the slight movements of the temperature responsive actuator are greatly multiplied and are transmitted in a substantially straight line.

Other objects and advantages which become

2

apparent upon reading the following complete description in connection with the accompanying drawing will be set forth in the appended claims.

In the drawing:

- 5 Fig. 1 is a plan view of a thermostatic snap-action switching device constructed in accordance with this invention, portions being broken away to more clearly illustrate.
- 10 Fig. 2 is a longitudinal section of the switching device shown in Fig. 1 and is taken along line 2—2 of Fig. 1;
- 15 Fig. 3 is a transverse section of the switching device shown in Figs. 1 and 2 and is taken on line 3—3 of Fig. 2.
- 20 The switch is mounted in a rectangular box-like casing 10, open at the top, and having a cover 11 which completes the closure and is removably attached to the casing 10 by screws 12. For simplicity, the casing is shown as being constructed of a suitable rigid dielectric material, but may, of course, be constructed of any suitable metal with suitable provision for electrical insulation.
- 25 Attached to the left end wall 13 of the casing, and on its exterior surface, is a circular expandible chamber element, generally indicated at 14. Element 14 comprises an outer circular, heavy-walled, rigid cup member 15 and an inner circular, thin-walled, flexible cup member 16, which is nested within the outer cup member and is attached thereto by a continuous welding together of the side walls of the cups as indicated at 17. A fluid-tight, expandible chamber defined by the bottom walls of the cup members is thus provided.
- 30 The bottom wall 15 of the outer cup is provided with an exterior projecting "frog-eye" extrusion 18 which is perforated and receives one end of a capillary tube 19. The tube 19 is rigidly attached within the perforation as by hard soldering at 20, to provide a fluid-type connection.
- 35 The other end of capillary tube 19 is connected to a remote rigid metal bulb 21 (which is shown substantially reduced in size), and its connection therewith is fluid-type. The bulb, the capillary tube, and the expandible chamber defined by the walls 15 and 16 of the cups form a closed fluid-tight system which is filled with a thermally expandible liquid. This liquid has a relatively high boiling point, sufficiently high at
- 40 least so that there is no vaporization within the operating temperature range of the device.
- 45 The amount of liquid placed in the system is such that the flexible wall 16 is normally substantially contiguous with the rigid wall 15 when the bulb temperature is below the operating tempera-
- 50
- 55

ture range, so that the full permissible deflection of the wall 16 may be utilized to extend the operating range of the device. The flexible wall 16 is stiffened against bulging by the provision of radially extending formed ribs 22, which provision, together with a practically incompressible, thermally expanding liquid, results in a relatively positive acting temperature responsive actuator. The amount of actuating movement in response to a unit temperature change in a device of this character will, of course, vary with the design and proportions of the device. However, considerations such as desirable design proportions, compactness, operating range, and the permissible deflection of the flexible metal wall 16 are limiting. In the contemplated construction, the effective actuating movement per degree of temperature change, Fahrenheit, is in the order of $\frac{1}{1000}$ of an inch for a minimum operating temperature range and may be as small as $\frac{1}{40,000}$ or $\frac{1}{10,000}$ of an inch for a maximum operating temperature range. The operating temperature range is increased and the movement per unit temperature change is decreased as the bulb is reduced with relation to the size of the expandable chamber.

A great multiplication of these slight movements must, therefore, be accomplished if sufficient movement is to be obtained to store energy in a resilient member for imparting a snap-action to the switch contacts, and if the temperature differential within which the switch operates is to be closely held, say in the order of 1° Fahrenheit. To achieve this multiplication, a lever multiplication system is provided, comprising a pair of flat triangular-shaped links 23 and 24 lying end to end with one side of each adjacent the other and extending longitudinally in the casing 10. Link 23 is provided with a socket 25 at its outer or left pointed end, which is adapted to receive the ball end 26 of a diaphragm follower member 27. The diaphragm follower 27 has a flat bearing surface 28 in engagement with the central portion of the flexible wall 16. A clearance aperture 29 is provided in the casing wall 13 to permit the passing through and oscillation of the link 23. The link 24 is provided with a similar socket 30 at its outer or right pointed end which is adapted to receive the ball end 31 of a threaded adjustment screw 32. The adjustment screw 32 is threadedly engaged in an internally threaded bushing 33, which is rigidly supported in the right-hand casing wall 34.

The adjustment screw 32 and the diaphragm follower 27 are in alignment and concentric with the circular element 14. The links 23 and 24 are also provided with opposed notches or recesses 35 and 36 in their adjacent ends which receive a pivot pin 37. The central portions of the adjacent flat ends of the links are cut back as indicated at 38 in order to reduce the bearing area between the pin 37 and the links. Links 23 and 24 are further provided with opposed lugs 39 and 40 at each edge of their wide inner ends, over each pair of which is placed a stressed spring-steel restraining clip 41. It will be seen that clip 41 will yield as the links 23 and 24 are rotated and that they will exert a resilient holding force to retain the pivot pin 37 in constant bearing engagement in the notches 35 and 36 as one link is caused to rotate by the rotation of the other. The links 23 and 24 are limited in their rotation toward alignment with each other by a stop member 41a supported in a side wall casing.

Link 23 is provided with a rigid extension 42

projecting rightward from its inner end. The extension 42 may be integral with the link 23 or may be a separate member rigidly attached thereto in any suitable manner.

At its outer end, the extension 42 carries a hemispherical button 43 which engages a shallow hemispherical recess 44 in a pivoted contact carrying arm 45 at a point near its pivoted end. At its other free end, the contact arm carries a movable contact 46 which cooperates with a stationary contact 47 to control a circuit. The contact arm 45 is mounted on a pivot 48 which is, in turn, supported in a bracket 49. The contact carrying arm 45 is of composite construction and comprises a stiff, non-flexing portion 50, extending from its pivoted end toward its free end, a flexible intermediate portion 51 near its outer free end, and a relatively stiff armature portion 52 at its outer end.

Directly above this outer armature portion 52, and supported by the cover member 11, is a permanent magnet 53. The stationary contact 47 is attached to the lower end of a contact adjusting screw 54, which screw is threadedly engaged in a conductor plate 55. The permanent magnet 53 is also attached to the conductor plate 55 in a suitable manner. The conductor plate 55 is attached to the cover 11 by means of a tubular rivet 56. This tubular rivet is internally threaded to receive a screw 57 which, together with the rivet, forms a terminal binding post for the convenient attachment of a circuit lead. A second terminal binding post is provided by a screw 58 and a tubular rivet 59, which rivet attaches the pivot supporting bracket 49 to the cover 11. A thin, very flexible, electrical conductor strip 60 is provided to insure electrical conduction from the inner end of the contact arm to the binding post. A return spring 61 bearing against the cover 11 at its upper end, and bearing at its lower end against the contact arm 45 at a point substantially in alignment with the button 43, urges the pivoted contact arm in a counterclockwise or switch opening direction.

It will be seen from the foregoing that the small horizontal movements of the follower member 27, due to expansion or contraction of the liquid, will be greatly multiplied at the point 43 on extension 42 where these movements are imparted to the contact arm 50. This multiplication is due to the relatively great rotational movement imparted to link 23 and its extension 42 by relatively slight horizontal movement of the follower 27, when this link is near alignment with its companion link 24, as shown. By making the links 23 and 24 substantially the same length, and by provision of the extension 42 which carries the button 43 at a point in approximate vertical alignment with the pivot point 31 of link 24, the path of movement of button 43 is caused to follow a substantially straight line. As a result of this arrangement, lateral sliding movement between the button 43 and the contact arm 50 is reduced and the operative connection between extension 42 and arm 50 may, therefore, be made quite simple, as shown. From the point of engagement of button 43 with contact arm 50, the movements of follower 27 are further multiplied in the arm 50, which extends oppositely and overlies the link 23 and extension 42, resulting in a compact arrangement.

In operation

The switching device is shown in Fig. 2 in a closed contact position. As the temperature to

which the bulb 21 is sensitive decreases, the liquid therein contracts and the follower 27 moves slightly toward the left, permitting the return spring 61 to rotate the link 23 clockwise and the contact arm 50 counterclockwise. The magnet 53, however, resists rotation of the outer end of arm 50 and, as a result, the resilient portion 51 is, therefore, flexed. When the resilient portion 51 is flexed to the point at which it will transmit sufficient force to overcome the attraction of magnet 53, the armature portion 52, together with the movable contact 46, will snap downward, thus breaking the contacts with a snap-action. The flat, flexible conductor 68 is of such flexibility as to offer no more resistance to rotation of arm 50 than does the usual pig-tail connection.

If, with the switch contacts now in open position, the temperature is increased, causing the follower 27 to move slightly toward the right, the link 23 will be rotated counterclockwise, opposing the turn spring 61 and rotating contact arm 50 in a clockwise or contact closing direction. The expansion of the liquid is, of course, characteristically slow, and the arm 50 is, therefore, slowly rotated until a point will be reached, prior to the meeting of the contacts, at which the magnetic attraction of magnet 53 will attract the armature 52 with sufficient force to cause the portion 51 to flex, and the armature 52 and the movable contact 46 to move rapidly ahead of the inner portion of the arm in a switch closing direction, thus imparting a closing snap-action.

By constructing the motion transmission mechanism of adequately rigid members so as to eliminate flexing at any point therein except the short portion 51, it will be seen that the required flexing to achieve the desired snap-action may be closely controlled or varied by simple calibration of the flexibility in one short portion or member.

It will also be seen that by locating this short flexing portion or member near the outer end of the contact arm as shown, the mass which moves rapidly during the snap-action is greatly reduced over the arrangement in usual constructions. By this reduction in mass, the energy is also greatly reduced, resulting in a substantially non-bouncing contact. A further advantage in the shortened, flexible portion or member 51 lies in the increased frequency and, therefore, the more rapid diminishing of its vibratory oscillations when stressed and released.

To adjust the device for operation at pre-selected temperatures within its operating range, the adjustment screw 32 is rotated. As the screw 32 is rotated outward, the temperature at which the device closes will be raised. The usual dial and indicator may be provided in connection with the adjusting screw 32. The stop member 41a limits the rotation of links 23 and 24 to a point just a few degrees from alignment.

The foregoing description is intended to be illustrative, not limiting, the scope of the invention being set forth in the appended claims.

I claim:

1. In a thermostatic switching device, a temperature responsive actuator having a definite path of motion in response to temperature change, a pair of links lying end to end in general alignment with said path of motion and being pivotally connected to each other at their adjacent ends, one of said links being pivotally connected at its other end to said actuator, and the other of said links being pivoted at its other end on a fixed pivot, a stationary switch contact

and a cooperating movable switch contact arranged to be moved by one of said links as it is rotated due to movement of said actuator.

2. In a thermostatic switching device, a temperature responsive actuator having a definite path of motion in response to temperature change, a pair of links lying end to end in general alignment with said path of motion and being pivotally connected to each other at their adjacent ends, one of said links being pivotally connected at its other end to said actuator and the other of said links being pivoted at its other end on a fixed pivot, cooperating stationary and movable switch contacts, and means carried by one of said links for moving said movable contact as said link is rotated due to movement of said actuator.

3. In a thermostatic switching device, a temperature responsive actuator having a fixed path of motion in response to temperature change, an adjustably fixed member spaced from said actuator and substantially in alignment with the path of motion of said actuator, a pair of links lying end to end between said actuator and said fixed member and being pivotally connected to each other at their adjacent ends, the other end of one link being pivotally connected to said actuator, and the other end of the other link being pivotally connected to said fixed member, cooperating stationary and movable switch contacts, and means carried by one of said links for moving said movable contact as said link is rotated due to movement of said actuator.

4. In a thermostatic switching device, a temperature responsive actuator having a definite path of movement, an adjustably fixed member spaced from said actuator and substantially in line with the path of motion of said actuator, a pair of links lying end to end between said actuator and said fixed member and being pivotally connected to each other at their adjacent ends, one of said links being pivotally connected at its other end to said actuator and the other of said links being pivotally connected at its other end to said fixed member, stop means for limiting the rotation of said link members in a direction toward alignment and to a point slightly before alignment, a stationary switch contact, and a cooperating movable switch contact arranged to be moved by one of said links as it is rotated due to movement of said actuator.

5. In a thermostatic switching device, a temperature responsive actuator having a definite path of movement in response to temperature change, a pair of link members lying end to end in general alignment with the path of motion of said actuator, said links being pivotally connected to each other at their adjacent ends, one of said links being pivotally connected at its other end to said actuator and the other of said links being pivoted at its other end on a fixed pivot, stationary and movable switch contacts, and means on one of said links extending beyond its pivoted connection with the other of said links for moving said movable contact as said link is rotated due to movement of said actuator.

6. In a thermostatic switching device, a temperature responsive actuator, a pair of spaced pivots, one of said pivots being movable by said actuator along a line substantially coinciding with a line passing through said spaced pivots, the other of said pivots being arranged to be adjustably fixed along said line, a pair of link members of substantially equal length lying end to end between said pivots, said links being piv-

totally connected to each other at their adjacent ends and pivoted at their opposite ends on said spaced pivots, one of said link members having a longitudinally projecting portion extending substantially to a perpendicular line intersecting the outer pivot of said other link, a stationary switch contact, and a cooperating movable switch contact arranged to be moved by the outer end of said projecting link portion as said link is rotated due to movement of said actuator.

7. In a thermostatic switching device, a temperature responsive actuator, a pair of spaced pivots, one of said pivots being movable by said actuator along a line substantially coinciding with a line passing through said spaced pivots, the other of said pivots being arranged to be adjustably fixed along said line, a pair of link members lying end to end between said pivots, said links being pivotally connected to each other at their adjacent ends and pivoted at their outer ends on said spaced pivots, one of said link members having a rigid, longitudinally projecting portion extending substantially to the outer end of said other link, and a pivoted contact carrying arm lying alongside and substantially coextensive with said link members, said arm being pivoted at one end and carrying a contact at its other end, and being operatively engaged by the

end of said projecting link portion at a point thereon near its pivoted end.

8. In a thermostatically operated control device, a pair of link members arranged end to end and being pivotally connected at their adjacent ends, a longitudinally adjustable pivot at the outer end of one of said links, a temperature responsive device having a pivotal connection with the outer end of the other of said links and arranged to act longitudinally thereon in response to temperature changes whereby said links are rotated thereby, a spring returned control member arranged to be actuated by the rotational movement of one of said links and arranged to normally urge said links in a direction toward alignment, and stop means for arresting the rotation of said links in a direction toward alignment to a point slightly short of alignment.
